UNITED STATES PATENT OFFICE

2,425,436

MUSICAL INSTRUMENT

Patrick McAuliffe, New York, N. Y.

Application September 25, 1943, Serial No. 503,803

12 Claims. (Cl. 84—378)

1

The present invention relates to new and useful improvements in musical instruments and more particularly to tone and volume control means for a harmonica.

An important object of the present invention is to provide mechanical means for circulating air through the harmonica to eliminate the use of a person's mouth for this purpose.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of one form of my invention.

Figure 2 is an end elevational view of the left hand end thereof.

Figure 3 is a similar view of the other end thereof.

Figure 4 is a longitudinal sectional view on a reduced scale taken substantially on a line 4—4 of Figure 1 and illustrating use of the rubber bulb for circulating air through the harmonica.

Figure 5 is a fragmentary front elevational view of the harmonica showing certain of the tone ports closed.

Figure 6 is a side elevational view of a modified form of tone and volume control means.

Figure 7 is a transverse sectional view taken on a line 7—7 of Figure 6.

Figure 8 is a longitudinal sectional view taken on a line 8—8 of Figure 6, and

Figure 9 is a transverse sectional view taken on a line 9—9 of Figure 1.

Referring now to the drawings in detail and first with particular reference to Figures 1 to 3, inclusive, the numeral 5 designates a cylindrical tube, open at each end, and having a longitudinal slot 6 in one side formed with inturned flanges 7 and adapted to snugly receive a conventional harmonica 8.

Adjacent one end of the tube is a ring 9 having a friction fit on the tube, said ring having an eye 10 attached thereto through which is loosely inserted a cord or other flexible member 11 to one end of which is attached a cap 12 adapted to fit over the end of the tube to close the latter and to the other end of the cord is attached a plug 13 adapted to tightly fit into the end of the tube to also close the tube, the cap and plug being interchangeable used.

A cylindrical cap 14 slidably fits over the other end of the tube to close said end, the cap 14 having an opening 15 in one side to form a discharge

2

port for air in the tube, the area of the port being controlled by the sliding adjustment of the cap 14 on the tube.

The harmonica may be secured in the slot 6 in any suitable manner, such as soldering or the like (not shown), or clamped therein by bolts 16 extended transversely of the tube adjacent each end of the harmonica the walls of the tube flexing sufficiently for this purpose.

10 The harmonica is played in the usual manner, that is, by a person circulating air therethrough by mouth, and the tone and volume may be regulated by removing and replacing the cap 12 or plug 13 on the end of the tube and by the adjustment of the cap 14 to regulate the size of the port 15.

In the form of the invention illustrated in Figures 4 and 5, the cap 12 or plug 13 are dispensed with and the end of the tube 17 is internally threaded as indicated at 17a for threaded engagement by a plug 18 provided with a rubber bulb 19 on its outer end communicating with a tube 20 inserted in the tube 17 and having a discharge opening 21 in one side of its inner end disposed behind the harmonica 22.

20 A cover 23 is cemented as at 23a or otherwise secured over the outer surface of the tone ports 24 of the harmonica, a few of the ports being uncovered or open as shown in Figure 4 for the intake and exhaust of air.

The other end of the tube 17 is closed by the adjustable cap 25.

25 Musical tones are produced by circulating air through the unobstructed ports of the harmonica 35 upon the expansion and contraction of the rubber bulb.

In Figures 7, 8 and 9, I have illustrated modified volume control means which comprises a ring 26 secured on the tube 27 adjacent one end 40 and from which a pair of lugs 28 and 28a project radially. A pin 29 bridges the lugs on which is pivotally mounted a bellcrank lever 30 having a handle 31 at one end and a link 32 pivoted at its other end and connected to the free edge of a cap 33 adapted to close the adjacent end of the tube 27. The cap 33 is swingably connected to the ring 26 by the interengaged eyes 34 and 35. A coil spring 36 bears against a glass lining 37 in the tube 27 and engages the inside of the cap 33 to urge the latter into an open position, while the lever 30 may be manually manipulated to close the cap.

45 A cord or flexible member 38 extends along the tube 27 through guides 39 and is attached to the cap 33 at its free edge in any suitable manner to

also close the cap in place of the lever 30 by pulling on the cord.

It is believed that the details of construction and manner of use of the device will be readily understood from the foregoing without further detailed explanation.

Having described the invention, what is claimed as new is:

1. A musical instrument comprising a tube open at each end and having a longitudinal slot in one side, a harmonica positioned in the slot with its mouth engaging edge outwardly of the tube, means carried by the tube for constricting the slot into clamping engagement with the sides of the harmonica and means for selectively closing both ends of the tube.

2. A musical instrument comprising a tube open at each end and having a longitudinal slot in one side, a harmonica positioned in the slot with its mouth engaging edge outwardly of the tube, a closure removably positioned on one end of the tube, and a cap slidably mounted on the other end of the tube and having an opening in one side adapted to be covered by the tube.

3. A musical instrument comprising a tube open at each end and having a longitudinal slot in one side, a harmonica positioned in the slot with its mouth engaging edge outwardly of the tube, a closure removably positioned on one end of the tube, and a cap slidably mounted on the other end of the tube and having an opening in one side having its area regulated by the tube.

4. A musical instrument comprising a tube open at each end and having a longitudinal slot in one side, a harmonica positioned in the slot with its mouth engaging edge outwardly of the tube, closures for the ends of the tube, and means for regulating the opening and closing of one of the closures.

5. A musical instrument comprising a tube open at each end and having a longitudinal slot in one side, a harmonica positioned in the slot with its mouth engaging edge outwardly of the tube, closures for the ends of the tube, manually operated means for actuating one of the closures in one direction and spring means actuating said one closure in an opposite direction.

6. A musical instrument comprising a tube open at each end and having a longitudinal slot in one side, a harmonica positioned in the slot with its mouth engaging edge outwardly of the tube, closures for the ends of the tube, a lever for moving one of the closures in one direction,

and spring means for moving said one closure in an opposite direction.

7. A musical instrument comprising a tube open at each end and having a longitudinal slot in one side, a harmonica positioned in the slot with its mouth engaging edge outwardly of the tube, closures for the ends of the tube, a flexible member for closing one of the closures, and spring means urging said one closure into its open position.

8. A musical instrument comprising a tube open at each end and having a longitudinal slot in one side, a harmonica positioned in the slot with its mouth engaging edge outwardly of the tube, a closure for one end of the tube, and an air pump secured in the other end of the tube.

9. A musical instrument comprising a casing having an opening therein, sound producing device fitted in the opening, and means for supplying air under pressure into the casing.

10. A musical instrument comprising a tube closed at one end, a harmonica in the side of the tube, and an expandable rubber bulb attached to the other end of the tube and adapted to circulate air through the harmonica.

11. A musical instrument comprising a tube open at each end and having a longitudinal slot in one side, a harmonica positioned in the slot with its mouth engaging edge outwardly of the tube, means for constricting the sides of the slot into clamping engagement with the sides of the harmonica, closures removably positioned on the ends of the tube, at least one of said closures embodying a plurality of closure devices adapted for selectively positioning on the tube, and a flexible member connecting the plurality of closure devices to each other and to the tube.

12. A musical instrument comprising a tube open at each end and having a longitudinal slot in one side, a glass lining in the tube, a harmonica positioned in the slot with its mouth engaging edge outwardly of the tube, closures at the ends of the tube, and means for adjusting at least one of the closures relative to the tube.
